UNITED STATES PATENT OFFICE.

EDDIE ESTELLE LOFLIN, OF FOXWORTH, MISSISSIPPI.

AUTOMATIC SHELL-TONGS.

1,281,799.

Specification of Letters Patent. Patented Oct. 15, 1918.

Application filed November 9, 1917. Serial No. 201,124.

To all whom it may concern:

Be it known that I, EDDIE E. LOFLIN, a citizen of the United States, and a resident of Foxworth, in the county of Marion and 5 State of Mississippi, have invented new and Improved Automatic Shell-Tongs, of which the following is a full, clear, and exact description.

This invention relates to tongs or similar 10 appliances for fishing or dredging for oysters, clams or the like at the bottom of a river or other body of water, and the same has particular reference to improved details of construction over the device set forth 15 and claimed in Letters Patent of the United States No. 1,233,074, issued to me on the 10th day of July, 1917.

More definitely stated, among the objects 20 of this present improvement is to simplify and improve the means for connecting the tongs, jaws or grabs to the handle; to simplify, strengthen and otherwise generally improve the spring means acting upon the jaws tending to close the same automatically; to improve the latch means serving to hold the tongs open in set position, and to generally improve the plunger devices and 25 ratchet means serving to prevent the undesired opening of the tongs after the latch 30 means have been tripped.

With the foregoing and other objects in view the invention consists in the arrangement and combination of parts hereinafter described and claimed, and while the invention 35 is not restricted to the exact details of construction disclosed or suggested herein, still for the purpose of illustrating a practical embodiment thereof reference is had to the accompanying drawings, in which like 40 reference characters designate the same parts in the several views, and in which

Figure 1 is a side elevation of the improved device in closed position as when being hoisted.

Fig. 2 is a similar view at right angles to the position of Fig. 1.

Fig. 3 is a vertical sectional detail on the line 3—3 of Fig. 2.

Fig. 4 is a fragmentary side elevation indicating the relative position of the parts when the jaws are being set in open position, but the operating lever not yet returned to the normal position, said position, however, being indicated in dotted lines.

Fig. 5 is a transverse sectional detail on the line 5—5 of Fig. 1.

Fig. 6 is a similar view on the line 6—6.

Fig. 7 is a transverse sectional detail on the line 7—7 of Fig. 3; and

Figs. 8 and 9 are detail perspective views 60 of the dog and hinge members referred to more particularly below.

This appliance in general terms comprises a pair of scoop shaped grabs or jaws 10 and 11 connected by means of rigid links 12 and 13 to the lower end of a rigid handle or pole 14 whereby the appliance or device is manipulated. The jaws 10 and 11 are adapted to swing away from each other into wide open position, the swinging movement being 70 compound and through arcs of circles having their centers at 15 and 16 at the upper ends of the links 12 and 13 respectively and around centers 17 and 18 at the lower ends of said links. The jaws are provided with a 75 pair of arms 19 projecting inwardly from the pivots 17 and 18 and are pivoted coaxially of each other at 20 upon a vertically reciprocating plunger 21. The arms 19 adjacent to the pivots 17 and 18 lie in the same 80 plane, but at their inner ends they are offset at 19' so as to lie on opposite sides of the plunger 21.

The lower portion of the plunger is indicated as being flat or rectangular in cross 85 section and is equipped with a relatively slideable foot piece 22 adapted to impinge against the bottom of the body of water for the purpose of tripping the device and permitting the jaws to close under the force of 90 a strong spiral spring 23 surrounding the upper rounded main portion of the plunger. Said spring 23 is housed within the hollow lower end of the handle 14 and is shown broken away for purposes of illustration. 95

A spring 24 of moderate strength is located between the foot of the slide and the lower end of the plunger and serves to keep the slide projected downwardly as far as permitted by stop pins or lugs 25 coöoperating 100 with side bars 26 of the slide. The offset portion 19' of each arm 19 is so designed as to form a stop shoulder 27 between which and the pivot 20 is located an upwardly projecting tooth 28. A latch 29 is pivoted 105 at 30 on each side of the slide 22 and flat portion of the plunger. Each latch includes a hook at its free end coöoperating with one of the teeth 28. A pair of links 31 are pivoted to the latches 29 and the lower portion 110 of the slide, these links serving to hold the latches down or in position to coöperate di-

rectly with the teeth 28 and with the stop shoulders bearing against the free ends of the latches to limit the downward movement of the pivot 20 with respect to the slide, 5 while the teeth 28 prevent the closing movement of the jaws until the latches are released from the teeth 28 as will be more fully set forth later. It will be noted from Fig. 4 that in the open or set position of the jaws 10 the pivot 20 lies below the plane of the centers of the pivots 17 and 18, the arms 19 acting in the nature of a toggle with respect to their common pivotal connection 20 through the plunger. The weight of the main portion 15 of the jaws or any other force acting thereon tending to close the same prematurely will be counteracted or resisted by the latches 29 coöperating with the teeth 28.

The lower end of the handle 14 is provided 20 with a strong ferrule reinforcing said lower end of the handle and serving as an anchorage for the links 12 and 13. Above the ferrule is located a collar 33 surrounding the handle and serving not only as a reinforcement for this hollow portion of the handle but also as a fulcrum support for a setting lever 34 pivoted at 35. A keeper 36 is located farther up on the handle and serves to hold the lever 34 in idle elevated 25 position at all times except when the lever is being manipulated to open and set the tongs.

The rounded upper portion of the plunger is provided with a longitudinal slot 37 of sufficient length to accommodate the swinging movement of the lever 34 and the swinging and reciprocating rod 38 pivoted at its upper end at 39 to the lever 34 and having a horizontal pin 40 at its lower end projecting through the slot 37 and extending across 40 and below the lower end of the handle. This pin 40 in its normal position lies substantially against the bottom of the ferrule 32 and with the lower end wall of the slot 37 bearing substantially against the lower face 45 of the pin. The rod 38 is provided between its ends with a cam surface 38'. This cam portion of the rod, when the rod is in normal position, does not extend laterally beyond the ferrule and handle, but when the 50 lever 34 is swung downward the upper end of the rod is carried laterally beyond the handle and causes the cam surface 38' of the rod to pass outwardly so as to project beyond the ferrule. Compare Figs. 1 and 4. 55 The force applied to the hand lever 34 acting first to swing the upper end of the rod laterally as just described serves eventually to force the plunger downward with respect to the handle, such force being applied 60 through the finger 40 and against the lower end of the slot 37. This action of the plunger straightens the toggle 19 and carries the pivot 20 thereof past the line of centers of the pivots 17 and 18 and brings the teeth 28 65 in position to be engaged and held by the

hooked latches 29. The keeper 41 is connected to the handle just above the ferrule 32 and serves to guard the rod 38 and hold it in position.

With reference now especially to Figs. 70 3 and 5 it will be noted that the upper portion of the plunger is provided with a rack 42 indicated as substantially coextensive with the rounded portion of the plunger. The main portion of the rack is set off or 75 spaced from the rounded portion of the plunger to provide a space 42' to accommodate the heavy expansion main spring 23. The bottom of the ferrule is designed to accommodate the plunger and rack and constitute a seat for the lower end of the spring so that when the plunger is forced downwardly and the spring is put under compression the lower end of the spring is held from movement with respect to the 80 handle. Any suitable form of dog may be provided to coöperate with the teeth of the rack 42 to prevent undesired opening of the jaws. For this purpose I provide that type of dog indicated in detail in Fig. 90 8, the same having a point 43 connected by means of a spring tongue 44 to a plate 45 extending transversely across and secured rigidly to one side of the ferrule 32. Adjacent and parallel to the spring tongue 44 95 I provide a projection 46 having an angularly formed flange 47 within or against which the cam portion 38' of the rod 38 is adapted to operate, to release the point 43 of the dog from the rack teeth or rather 100 to hold said point out of the path of said teeth when the rack and plunger are projected downwardly under the force applied to the lever 34. In other words immediately after the lever 34 is swung outwardly 105 from the keeper 36, the rod 38 acts through the projection 46 to throw said projection and dog outwardly putting the spring 44 under tension, the point of the dog being then free from the rack teeth 42. See Fig. 110 4. During the latter portion of the movement of the lever and the projection of the plunger the cam surface or edge 38' acts to hold the dog in the position just indicated. If, however, the lever 38 be maintained in its normal elevated position the dog 43 will always be in position to engage the rack teeth and prevent undesired downward movement of the plunger. The upper 115 ends of the links 12 and 13 are provided with T-shaped heads constituting the aforesaid pivots 15 and 16 respectively. The head 15 is shorter at one end than at the other and lies within a concavity 48 formed across the lower portion of a hinge plate 120 49. This plate is connected at its upper portion to the plate 45 of the dog, one side of the plate 49 being cut away to provide a clearance for the spring tongue 44. A hinge plate 50 is secured at the opposite 125 130

side of the ferrule and is formed with a bearing concavity 51 to accommodate the T head 16 of the opposite link.

With the foregoing specific description of the preferred embodiment of the invention, its operation may be briefly set forth as follows: In order to open and set the jaws in position to be lowered to the bottom of the river or the like the operator 10 grasps the lever 34 and swings it down into or toward the position shown in full lines in Fig. 4. This action, through the rod 38 and finger 40 projects the plunger downwardly placing the strong main spring 23 under sufficient tension to close the jaws at the intended time. This movement of the lever and rod throws the dog 43 out of the path of the rack teeth 42 and when this movement is completed the locking latches 29 20 engage the teeth 28 and hold the jaws in wide open position. The force of the spring 24 being brought into action at the proper time insures that during this opening and setting movement the slide 22 will occupy 25 its downward position with respect to the plunger and insuring locking action of the latches. With the parts thus positioned as indicated in Fig. 4 a very rigid structure is provided, for with the lever 34 and connecting rod 38 restored to normal elevated position and the dog 43 acting upon the teeth of the rack 42 no relative movement of the jaws around their pivots 17 and 18 can take place until the latches 29 are released. In other words the plunger will 35 ordinarily remain projected downwardly by the fact that the pivot 20 has passed below the line of centers of the pivots 17 and 18 and the latches are in engagement with the 40 teeth 28. Any force acting upon the point of either of the jaws tending to swing the same upwardly around the pivot 17 or 18 and tending to swing the pivot 20 downwardly will be resisted by the dog 43 holding 45 the plunger from such movement, while the link 12 or 13 of such jaw constitutes a rigid strut preventing upward movement of the pivot 17 or 18. Obviously the connecting arm 19 will prevent lateral swinging 50 movement of the jaw until the latches are released. When the foot of the slide 22 impinges against the bottom of the body of water or other obstacle it is forced upwardly against the spring 24 carrying upwardly the latches 29 and releasing the same from the teeth 28, when the main spring 23 will be free to carry upwardly the entire plunger with its slide and the inner coaxially pivoted ends of the arms 19 and 60 closing the jaws.

While I have shown and described the inner ends of the latches 29 as pivotally attached at 30 to the plunger 21 whereby there is a swinging movement provided for the 65 latches with respect to the plunger, I show

as an alternative means for attaching the latches, the slide 22 provided with holes 22^a and each of the latches provided with a hole intermediate of its ends at 29^a so that by extending a pin, or its equivalent, through 70 the registering holes 29^a and 22^a the latches may be in effect rigidly connected to the slides by virtue of the links 31, all of which parts are connected to the same slide member. The spring 24, however, serves to cause 75 the hooks of the latches 29 to snap over the teeth 28 in the setting of the devices into the open position of Fig. 4, and likewise the slide when it impinges against the bottom of the water will be forced upwardly against 80 the tension of the spring 24 to release the latches in the tripping action.

I claim:

1. In automatic shell tongs, the combination with a rigid handle having a hollow 85 end, jaw members, and pivoted link connections between the handle and the jaw members, of means operating within the handle and pivotally connected to the jaw members to control the movement of the jaw members, 90 said controlling means comprising a rigid member reciprocating in the hollow handle, and a strong coil spring housed within the handle and acting upon the rigid member to move the same and the jaw members in one 95 direction.

2. In shell tongs, the combination with a rigid handle having at one end an axial bore, a ferrule fitted upon said end and having a hole therethrough and registering with said 100 bore but of smaller size, a pair of jaws, pivotal connections between the jaws and the handle, said jaws including a pair of inwardly projecting arms and a rigid member having one end located in the handle bore 105 and reciprocating through the ferrule hole, of a coil spring surrounding one portion of the rigid member within the handle and bearing at one end against the ferrule, means pivotally connecting the inner ends of the 110 arms to the rigid member to move the same in one direction placing said spring under tension and opening the jaws, and means acting to hold the jaws open.

3. In automatic shell tongs, the combination with a rigid handle having a hollow lower end, a ferrule fitted upon said end and having a central hole therethrough registering with the hollow portion of the handle but of smaller size, a pair of jaws, a pair of 120 rigid links pivotally connecting the jaws to the ferrule and a plunger reciprocating through the ferrule hole, of means pivotally connecting the inner portions of the jaws coaxially of each other upon the plunger, a 125 spring located within the hollow handle, one end of the spring being connected to the end of the plunger and the other end of the spring being seated upon the ferrule, said spring serving to elevate the plunger and 130

close the jaws, manually actuated means adapted to act upon the plunger against the force of the spring to open the jaws, and means movably mounted upon the plunger 5 to lock the jaws open.

4. In shell tongs of the character set forth, the combination with a rigid handle, a pair of jaws pivotally supported thereon and a rigid plunger movable endwise along the 10 handle and connected to the jaws to control the opening and closing movements thereof, of a rigid slide mounted upon the lower end of the plunger and adapted for independent endwise movement thereon, latch devices 15 carried by the plunger and the upper end of the slide and coöperating with the jaws to hold them open, said slide being movable as a result of impact with the bottom of the water to release said latch devices, and 20 spring means acting between the slide and the plunger serving to normally hold the slide extended downwardly.

5. In automatic shell tongs, the combination with a rigid handle, a plurality of jaws 25 movable toward and from each other, anchor means supporting the jaws upon the handle and a plunger movable along the handle and having pivotal connection with the jaws to positively cause the opening and closing 30 movements thereof, means to move the plunger, a slide mounted upon the lower end of the plunger and adapted to impinge against an obstacle when the tongs are to be closed, said slide being movable independently 35 along the plunger, a spring acting between the slide and the plunger tending to prevent the independent movement of the slide, and a plurality of latches connected to the plunger and the slide and acting upon the respective jaws to hold the jaws open. 40

6. In automatic shell tongs, the combination with a handle, a plunger reciprocating endwise therealong, a pair of jaws suspended from the handle, said jaws having inwardly projecting overlapping arms and pivotal connections between said arms and the plunger, said arms having locking teeth, 45 of a rigid member slidable lengthwise upon the lower end of the plunger, means acting between the rigid member and the plunger tending to hold the rigid member projected downwardly with respect to the plunger, and a pair of latch members pivoted upon the plunger and the upper end of the rigid 50 member and coöperating with said teeth to hold the jaws open when the plunger and rigid member are projected downwardly. 55

7. In automatic shell tongs, the combination with a rigid handle, a pair of rigid 60 links pivoted to the lower end of the handle, a pair of jaws pivoted to the lower ends of the links, and a plunger movable lengthwise along the handle having pivotal connection with the jaws, and means to positively move 65 the plunger endwise to open and close the

jaws; of a slide embracing the lower end of the plunger and adapted to move endwise thereon independently of the movements of the plunger, the lower end of the slide constituting a foot adapted to impinge against 70 an obstacle, a coil spring located between the foot and the lower end of the plunger tending to keep the slide projected downwardly, a pair of locking latches carried on the plunger on opposite sides of the slide and co- 75 operating with shoulder portions of the jaw arms to prevent undesired movement thereof, and link members connected to the latches and the foot acting between the lower end portion of the slide and said 80 latches serving to cause the latches to operate when the plunger and slide are projected downwardly.

8. In automatic shell tongs of the character set forth, the combination with a rigid 85 handle, a pair of jaws suspended therefrom, a plunger movable lengthwise of the handle and pivotally connected to the jaws to open and close the same, and lever devices acting between the handle and the plunger to project the same to open the jaws, of locking and tripping devices mounted and movable upon the lower end of the plunger serving to hold the jaws apart, and a coil spring mounted within the handle and acting 90 directly upon the upper end of the plunger to elevate the same and close the jaws when said tripping devices are sprung by impact against an obstacle.

9. In shell tongs, the combination of a 100 handle, a plunger reciprocating in the end of the handle, said plunger having a rack connected thereto and reciprocating with the plunger in the handle, a pair of jaws, pivotal connections between the jaws and the plunger, a pair of rigid hanger links pivoted to the jaws on opposite sides of the plunger connections, means pivotally connecting the upper ends of the links to the handle, said last mentioned means including 105 a pair of bearing plates, a spring actuated dog secured to one side of the end of the handle by means of one of said plates and coöperating with the rack teeth to prevent undesired movement of the rack in one direction, and means serving to positively project the plunger, said last mentioned means including a reciprocating rod acting upon said dog to remove the same from engaging position. 110

10. In shell tongs, the combination of a handle having a hollow end, a ferrule fitted upon said end and having a hole therethrough registering with the hollow end but smaller in diameter, a plunger having a 115 slotted round upper end reciprocating through said ferrule hole, a coil spring within the hollow handle surrounding the round portion of the plunger, one end of the spring being connected to the end of the 120

130

plunger while the other end of the spring is seated upon the ferrule, a rack secured to one side of the round portion of the plunger, a spring operated dog on one side 5 of the ferrule and coöperating with said rack teeth, said dog including a transverse engagement plate, a rack engaging point, a spring tongue between the plate and the point, and a lateral projection extending

from the point remote from the plate, and 10 means carried by the handle for manually projecting the plunger downwardly, said last mentioned means including a reciprocating rod coöperating with said lateral projection of the dog to hold the same out of the 15 path of the rack teeth while the plunger is being manually projected.

EDDIE ESTELLE LOFLIN.
